SAMUEL KAHN, OF NEW YORK, N. Y., ASSIGNOR OF ONE-THIRD TO MONROE FRIEDMAN
AND TWO-THIRDS TO ANTHONY WILLIAM DELLER, BOTH OF NEW YORK, N. Y.

SOUND RECORDING SYSTEM

Application filed February 25, 1929. Serial No. 342,338.

This invention relates to sound-recording systems and more particularly to the art of recording sound on a photographic film and has for its object the provision of an improved system.

Heretofore various systems have been employed for recording sound by translating sound waves into light effects which were made effective upon a traveling photographic film. In this manner variations in the intensity or the amount of light which were effective upon the film were acoustically controlled. The systems thus far proposed were all objectionable in that very rapid variations of light could not be obtained. Some systems were defective in that there was a mechanical distortion due to resonance. Other systems were too sluggish and would not respond practically instantaneously to sound, electric current and light effects.

I have discovered a system which is free from the objections noted heretofore and which is a substantial improvement over prior systems.

In accordance with my invention I provide a system of recording sound on photographic film which is accurate, reliable and sensitive. With my improved system it is possible to obtain fidelity of translation of sound waves into electric currents and light effects whereby practically all of the sound from the human voice or from various instruments, including the melodious over-tones, may be faithfully recorded.

Generally speaking, my invention contemplates providing a device which is very sensitive to sound and to electric currents and which is capable of causing the emission of light which changes practically instantaneously with changes of electric current and sound. In this manner it is possible to make a faithful record of music, human voice, or other sounds on a photographic film and it is possible to obtain practically perfect synchronism between the individual pictures of a motion picture and accompanying sound. My device is of such a construction that I may use a standard size motion picture film with standard size pictures thereon and I may record the sound on the film located to the

right or to the left of the pictures and preferably on the film situated between the outermost side of the pictures and the innermost side of the perforations. In some instances I record on the two sides of the pictures in order to get special results, such as music from one source and the human voice or other sounds from other sources. Various other uses may be made of two records, such as recording a frequency record on one side and a volume record on the other side in order to obtain a reproduction which will be true and will be free from distortion.

The invention will be described more in detail with particular reference to the accompanying drawing, in which:

Fig. 1 is a sectional view of an embodiment of my invention as applied to the holder plate of a motion picture camera, certain well known parts of the latter being omitted for the sake of clarity;

Fig. 2 is a fragmentary view of a portion of the camera holder plate with my improved record-width regulating device attached thereto;

Fig. 3 is an enlarged side view of the reflecting prism secured to the vibrating armature of my improved device illustrated in Fig. 1;

Figs. 4 and 5 are end elevations of the prism shown in Fig. 3 with different types of light windows;

Fig. 6 is a plan view of the armature supporting the light-reflecting prism;

Fig. 7 is a fragmentary portion of a standard photographic film with standard size pictures thereon and with two of my sound records located between the outermost sides of the pictures and the innermost sides of the film apertures;

Fig. 8 is a front elevation, somewhat fragmentary, of the camera holder plate with my record-width regulator attached thereto and with a portion of a film located in the rear thereof; and

Fig. 9 is a modified embodiment of my invention.

Referring now more particularly to Fig. 1, the numeral 1 designates a light-tight casing of my improved device which is secured

by means of a wall 15 and screws 15-a to a film supporter or plate 14 mounted within a camera (not shown). This film supporter, as is well known, is mounted an appropriate distance from the camera aperture, usually the distance of about 19 to 20 pictures. Within the casing 1 is mounted an electro-magnetic unit 2 which is composed of a U-shaped magnet provided in the well-known manner with 10 pole plates 5. Between these sides of the U-shaped magnet and adjacent to the inner side of the pole plates 5 an annular coil 4 is located. Through the annular coil 4 and between the pole plates 5 an armature 7 projects as a cantilever arm from its mounting 3 which is rigidly secured to the sides of the U-shaped magnet 2.

The electromagnetic coil 4 is connected to a source of electrical energy such as batteries 20 36-a and to a microphone and suitable amplifying apparatus designated as 36. The microphone, of course, can be carried to and placed at any remote point or location where the sound is being generated. In this way, it 25 is possible to have the camera which is taking the motion pictures located in one place and the microphone which is used in the recording of the sound located near the music, the talking actors or the like. By properly magnifying the electrical currents received from 30 the microphone in a manner well understood in the art, electrical currents of practically any desired value may be impressed on the electromagnetic coil. Due to variations in the 35 electrical current impressed on the electro-magnetic coil it is possible to obtain appropriate variations in the electro-magnet field. The variations in the electro-magnetic field cause vibrations of the armature 7. These 40 vibrations are thus proportional to the modulations of sound impinging upon the microphone.

The vibrating armature is provided at its free end with a light reflecting prism 6 which 45 is securely mounted over a light aperture 26. The prism may be secured in any appropriate manner such as by cementing with an adhesive binder or by a clip fastened around the bottom of the armature and the sides and/or top. With this arrangement the prism will 50 vibrate with the vibrating armature. Faces a, b and d (see Figs. 3-5) of the prism are preferably completely covered with some opaque light-reflecting substance like a silvered mirror. Face e is similarly covered 55 with the exception of the pin hole or bulls eye 24 or slit 25 which is left uncovered for the emission of light from within the prism. This light is supplied from a constant source 60 of light such as an electric bulb 8 which is fitted in a condenser tube 13 provided with condenser lenses 9 and 10. Adjustment of the condenser may be had by grasping knob 11 and moving the outer portion of tube 13 in 65 order to concentrate the light within the

prism. Electric bulb 8 may be energized in any well known way as by the use of an electric battery 12.

Light coming from within the condenser 13 is reflected from the inner face of the prism 70 through the bulls eye 24 or slit 25 and "sound-recording" window 22 in the film supporter 14 to the photographic film 16. The "sound" is recorded in record-portion 19 which is located between the outermost sides of the pictures and the innermost sides of the rectangular holes for the star-wheels of the projecting camera. In some instances I prefer to provide a regulator 22-a for controlling the width 75 of the bands or waves of "sound" recorded on the film. As may be seen from Figs. 2 and 8 the regulator 22-a may be adjusted back and forth by use of adjusting screws 23. It is to be observed that with the aforesaid organization it is possible to use a standard motion 80 picture film with standard-size pictures thereon and to record the "sound" in that portion of the film situated between the outermost sides of the picture and the innermost sides 85 of the starwheel guide holes. 90

In the operation of my improved sound-recording device the motion picture camera is operated in the usual manner and the microphone is positioned near the scene of action, music, or whatever source of sound 95 is to be recorded. With my arrangement the camera may be located in one position whereas the microphone may be located some remote point therefrom. As the sound to be recorded becomes effective upon the microphone, electrical currents set up in the microphone system which cause a variation in the strength of the electro-magnet. The variations in the electro-magnet set the armature 100 with its prism into vibration which continues as long as sound is being transmitted through the microphone. Due to the vibrations of the armature light issuing from the bulls eye 105 24 or slit 25 is vibrated back and forth about a central line or axis (shown by a full line in Fig. 1). This vibrating light affects the photographic film in a well known manner and makes a zig-zag record line which looks to the naked eye like bands 21. Sound can thus be instantly and faithfully recorded on 110 a moving photographic film in a simple manner and without any complicated apparatus. 115

In Fig. 7, I have shown a fragment of a film 27 upon which two sound records have 120 been recorded, a record 21 on the right-hand side of the film and a record 28 on the left-hand side. As explained heretofore these records may be used for any variety of purposes. For instance, one can be the record of music and the other that of the human 125 voice. Many other variations are possible as one skilled in the art will readily understand.

A modified embodiment of my invention is illustrated in Fig. 9. This embodiment has the same fundamental principles incorpor- 130

ated therein as the structure described hereinabove except a "phone" type of vibrator is used instead of an electromagnetic type. In the modified embodiment the microphone 5 system 36 is connected to a magnetic "phone" coil 35 which is provided with a pole 39. This magnetic coil is mounted on insulators 38 within casing 29 which is screwed on to or otherwise secured to housing 30. Clamped 10 between this housing 30 and the casing 29 is a diaphragm D provided with a mirror-like polished or silvered reflective surface.

Casing 30 is secured to a film supporter, or plate 14 by means of a plurality of screws 15 37 or the like and is cast so as to provide a mounting M for a light 31 and condenser 34 with lenses 32 and 33 and a light tube L at an oblique angle to said mounting. Electrical energy is supplied to electric light 31 by 20 means of batteries 40. When the electric light is energized a light beam is emitted to the diaphragm and is reflected therefrom in approximately a central line of tube L. This line passes through sound-recording aperture 25 22 and lies about in the middle of the sound record 21.

When motion pictures are taken the sound is transmitted to the microphone which causes variation in the electro-magnetic field 30 and a vibration of the diaphragm. As the diaphragm vibrates the reflected line oscillates back and forth and causes a variation in the light impinging upon the film 16. The light waves are depicted in somewhat exaggerated form as zig-zag lines, although in a finished film the lines are very close together and appear like a series of transverse lines or bands zig-zagging back and forth about a central line or axis.

40 Although I have described specific embodiments of my invention it is to be understood that the invention is not restricted to such particular embodiments. Various modifications thereof in detail and in the 45 arrangement of the parts may be made by those skilled in the art without departing from the invention as defined in the claims. For example, the armature may be developed at its free end as a light reflecting surface 50 so that the necessity of having a special prism for this purpose may be dispensed with. The metal of the armature may be electro-plated with nickel and/or chromium to provide a mirror-like reflecting surface.

55 I claim:

1. In apparatus for recording motion pictures and sound on a photographic film that improvement which comprises in combination 50 a microphone, a source of electrical energy for actuating said microphone, an electro-magnetic coil connected to said microphone and source of energy whereby modulations of sound impinging upon said microphone are converted into electro-magnetic variations in said coil, an armature located

closely adjacent to said coil so as to be vibrated by the said electro-magnetic variations, said armature being fixed at one end and adapted to be acted upon magnetically at an intermediate portion thereof by the 70 aforesaid electro-magnetic coil while the other end is free to vibrate, a light aperture provided in said armature adjacent to the free end thereof; light reflecting prism mounted over the light aperture of said armature and capable of vibrating therewith, said prism being covered practically completely with an opaque substance and having a small aperture for light on one face and a pin hole on a face at right angles thereto for 80 the emission of a sharp, concentrated, intense beam of light reflected from the inclined face of the prism; a source of light positioned to direct a beam of light on said light-reflecting prism through said small light aperture, 85 and a sound aperture incorporated in the film supporter of the recording apparatus in alignment with a beam of light normally reflected by said light-reflecting means whereby the light reflected by the vibrating light-reflecting means on the armature is effective 90 for making a sound record on the photographic film.

2. In apparatus for recording motion pictures and sound on a photographic film that 95 improvement which comprises in combination a microphone, a source of electrical energy for actuating said microphone, an electro-magnetic coil connected to said microphone and source of energy whereby modulations of 100 sound impinging upon said microphone are converted into electro-magnetic variations in said coil, a cantilever armature located closely adjacent to said coil so as to be vibrated by the said electro-magnetic variations, said 105 armature being fixed at one end and adapted to be acted upon magnetically at an intermediate portion thereof by the aforesaid electro-magnetic coil while the other end is free to vibrate, a light aperture provided in said 110 armature adjacent to the free end thereof; light-reflecting prism fixedly mounted over said light aperture of said armature and capable of vibrating therewith, said prism being covered practically completely with an opaque substance and having a small aperture for light on one face and a pin hole on a face at right angles thereto for the emission of a sharp, concentrated, intense beam of light 115 reflected from the inclined face of the prism; a source of light positioned to direct a beam of light on said light-reflecting prism through said small aperture, and a sound aperture incorporated in the film supporter 120 of the recording apparatus in alignment with a beam of light normally reflected by said light-reflecting means whereby the light reflected by the vibrating light-reflecting means on the armature is effective for making a 125 sound record on the photographic film.

3. In apparatus for recording motion pictures and sound the combination comprising an electro-magnetically vibrated armature having light-reflecting prism mounted over a 5 light aperture at the free end thereof and included in a microphone-circuit, said prism being covered practically completely with an opaque substance and having a small aperture for light on one face and a pin hole on a 10 face at right angles thereto for the emission of a sharp, concentrated, intense beam of light reflected from the inclined face of the prism, a moving photographic film, and means for causing light to impinge on said 15 vibrating armature for reflection to said film in accordance with variation of sound received by said microphone.

In testimony whereof I have hereunto set my hand.
